UNITED STATES PATENT OFFICE.

MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

CLUTCH MECHANISM FOR POWER-DRIVEN MACHINES.

Application filed August 5, 1921. Serial No. 490,040.

To all whom it may concern:

Be it known that I, MARTIN HEMLEB, a citizen of the United States, residing at Elizabeth, in the county of Union and State of New Jersey, have invented certain new and useful Improvements in Clutch Mechanisms for Power-Driven Machines, of which the following is a specification, reference being had therein to the accompanying drawings.

This invention relates to power-transmitting clutches, more particularly of the friction type represented in my Patent No. 1,409,444, granted March 14, 1922, and has for an object to provide an improved clutch affording nice control of the speed of the driven clutch-element or machine by an inexperienced operator.

A further object of the invention is to reduce to a minimum the end-thrust friction between the clutch-controlling member and the driven clutch-element and to overcome the tendency of the endwise movable clutch-element to stick on its shaft.

In the particular embodiment of the invention illustrated, the foregoing objects are attained by interposing a light spring between the driving and driven clutch-elements and by opposing the action of this spring tending to separate the clutch elements by the action of a stronger spring carried by a clutch-controlling member. This second spring preferably receives the thrust of a bearing piece which is formed with a socket to receive one spherical end of a thrust-rod, the opposite spherical end of which is received within a socket at the center of the endwise movable clutch-element. Thus, the pressure of the clutch-controlling element is always exerted centrally of the endwise movable clutch-member, where the frictional resistance is a minimum. The opposed springs permit a gradual application of pressure of one clutch-element against the other, over a considerable range of movement of the operating treadle. When the pressure exerted by the operator upon the clutch-element is relieved, the spring interposed between the clutch-elements operates to separate them without cramping the slideable clutch-element on its supporting shaft.

The various features of the invention will be understood from an inspection of the ac-

companying drawings and the following detailed description of the mechanism illustrated therein.

In the drawings, Fig. 1 is a side elevation, partly in section, of a sewing machine embodying the invention, the parts being in non-driving position; and Fig. 2 is a fragmentary view similar to Fig. 1 with the parts in driving position.

The present clutch mechanism is particularly adapted for driving a sewing machine of the usual type having a bed 1, and goose-neck 2 in the horizontal member 3 of which is journaled the main-shaft 4 connected, as usual, to drive the sewing and feeding mechanisms of the machine. The main-shaft projects exteriorly of the goose-neck through the bearing boss 5 and loosely carries the live clutch-element 6 which is constantly driven by the electric motor 7 having its power-shaft 8 arranged transversely of and below the main-shaft 4 and connected to the latter by means of the spiral gears 9-10. The live clutch-element is provided with a conical friction-driving surface 11.

Mounted to slide upon but rotate with the shaft 4 is the driven clutch-element 12 having the key-slot 13 which slidably fits over the key 14 let into the shaft 4, and is also provided with a conical friction facing 15 complementary to the driving surface 11. The driven element 12 is constantly urged out of engagement with the live clutch-element 6 by means of the coil spring 16 surrounding the shaft 4 and interposed between the driven clutch-element and a washer 17 backed up by a split-collar 18 tightly clamped upon the shaft 4.

Tightly fitted to the outer end of the shaft-receiving aperture 19 in the driven clutch-element 12 is a thrust-receiving button 20 formed centrally with a socket for the ball-end 21 of a thrust-rod 22, the opposite ball-end 23 of which is socketed centrally of the pressure-member or head 24 of a pin 25 slidably mounted in a sleeve 26 fixed within a boss 27 at the free end of the usual clutch-operating lever 28. A spring 29 strong enough to overcome the spring 16 is interposed between the head 24 and the end-wall 30 of the sleeve 26. A collar 31 fixedly secured to the end of the pin 25 projecting through the end wall 30 of the sleeve, limits the advance of the head 24 by the spring 29.

The clutch-controlling lever is fulcrumed, as represented in my said co-pending application upon the pivot 32 sustained by the bracket 33 secured to the goose-neck 2; the bracket 33 terminating in a stationary brake-arm 34. The clutch-controlling lever 28 is formed with a brake-arm 35 adapted to clamp the driven clutch-wheel 12 against the stationary brake-arm 34 to quickly and smoothly stop the sewing machine when driving relation between the clutch-elements is interrupted. The downwardly extending arm 36 of the clutch-controlling lever may be operated by a link connection 37 with a lever-arm 38 fixed to a rock-shaft 39 beneath the bed 1, to which rock-shaft is also connected the treadle-operated arm 40. A spring 41 tends to restore the arm 38 to the position shown in Fig. 1 and thereby apply the brake 35 to the driven clutch-element 12.

When the treadle-arm 40 is pulled downwardly, the braking pressure of the arm 35 upon the driven clutch-element 12 is relieved and the pressure of the spring 16 is balanced by the pressure of the spring 29 before the said clutch-element is moved over against the live clutch-element. This provision allows the operator to freely turn the wheel 12 by hand to raise the needle from the work at the end of a sewing operation or to set the needle in the work preparatory to turning a square corner. A further pull upon the arm 40 compresses the spring 29 sufficiently to overbalance the spring 16 and lightly press the driven wheel into engagement with the live clutch-element. Still further movement of the arm 40 over a considerable range effects a gradual increase of pressure of the wheel 12 against the driving element 6, with a consequent increase in speed of the driven element. By thus spreading the control of the driven element over substantially the full range of treadle movement, an inexperienced operator may readily obtain any desired sewing machine speed.

The use of the thrust-rod for applying the opposed pressures centrally of the driven element and clutch-arm, respectively, reduces friction to a minimum and greatly increases the useful life of the device.

While the present invention is particularly adapted for use in connection with the sewing machine driving and controlling mechanism disclosed in my Patent No. 55 1,384,464, granted July 12, 1921, it is evident that it may be used with various other mechanisms within the spirit and scope of the invention.

Having thus set forth the nature of the 60 invention, what I claim herein is—

1. In a clutch device, a live clutch-element, a driven clutch-element having an axially disposed socket, a clutch controlling lever, and a thrust-rod received at one extreme end in the axial socket in the driven clutch-element and at its other extreme end connected to said clutch-controlling lever, said thrust-rod being free of support between its ends. 70

2. In a clutch device, a live clutch-element, a driven clutch-element, a clutch-controlling lever, a pressure member resiliently mounted on said lever, and a thrust-rod free of support between its ends and connected at its ends to said pressure-member and driven clutch-element which form the sole direct supporting means for said rod. 75

3. In a clutch device, a live clutch-element, a driven clutch-element having an axially disposed spherically-surfaced socket, a spring tending to separate said elements, a clutch-controlling lever, a pressure-member resiliently mounted on said lever and formed with a spherically surfaced socket, 85 and a thrust-rod having spherically surfaced ends received in said sockets and free of support between its ends.

4. In a clutch device, a live clutch-element, a driven clutch-element, a clutch-controlling lever, a sleeve carried by said lever, a pin slidably mounted within said sleeve and formed with a socketed pressure-head, a spring surrounding said pin within said sleeve, and a thrust-rod received at one end 90 by said socketed pressure-head and at its other end socketed in the driven clutch-element, axially of the latter. 95

In testimony whereof, I have signed my name to this specification.

MARTIN HEMLEB.
